CLAIM

The ornamental design for a fruit punnet as shown and described.

DESCRIPTION

FIG. 1 is a left-side view of a fruit punnet, showing our new design;

FIG. 2 is a front view thereof;

FIG. 3 is a bottom view thereof;

FIG. 4 is a top view thereof;

FIG. 5 is an above and right-side perspective view thereof from a first angle;

FIG. 6 is an above and left-side perspective view thereof from a first angle;

FIG. 7 is an above and right-side perspective view thereof from a second angle;

FIG. 8 is an above and left-side perspective view thereof from a second angle;

FIG. 9 is a below and right-side perspective view thereof;

FIG. 10 is a below and left-side perspective view thereof;

FIG. 11 is a cross-sectional view of the fruit punnet according to lines 11-11 shown in FIG. 4; and,

FIG. 12 is a cross-sectional view of the fruit punnet according to lines 12-12 shown in FIG. 4.

The broken lines shown represent portions of the fruit punnet that form no part of the claimed design.
